Anton Fazekas, San Francisco, Calif.

Application May 22, 1933. Serial No. 48,183

Term of patent 3½ years

To all whom it may concern:

Be it known that I, ANTON FAZEKAS, a citizen of the United States, residing at San Francisco, in the county of San Francisco and State of California, have invented a new, original, and ornamental Design for a Combination Illuminated House Number Plate, Letter Drop Opening, and Signal Push Button, of which the following is a specification, reference being had to the accompanying one sheet of drawing forming part thereof.

Figure 1 is a front view of a combination illuminated house number plate, letter drop opening, and signal push button, showing my new design;

Figure 2 is a top view thereof;

Figure 3 is a side view.

I claim:

The ornamental design for a combination illuminated house number plate, letter drop opening, and signal push button as shown.

ANTON FAZEKAS.
